UNITED STATES PATENT OFFICE.

RALPH W. MORRISON, OF OMAHA, NEBRASKA.

PHONOGRAPH.

Application filed January 13, 1920. Serial No. 351,150.

To all whom it may concern:

Be it known that I, RALPH W. MORRISON, a citizen of the United States, residing at Omaha, in the county of Douglas and State 5 of Nebraska, have invented certain new and useful Improvements in Phonographs, of which the following is a specification.

This invention relates to an improvement in phonographs, and more particularly to 10 the sound conducting tube and sound reproducer of a phonograph, and has for its object, broadly, to provide such a construction that at least three diaphragms may be used and that sounds may be reproduced 15 from any of the disc-records now in use. The invention includes a sound reproducer adapted to be rotated for adjustments longitudinally of the sound conducting tube to dispose its apertures in register with the 20 apertures of said tube, and to provide a required weight or pressure for the several styli in their playing positions, and also to dispose each stylus, when in its playing position, at the same distance from the axis 25 of movement of the tone-arm.

It is well known to those versed in the art that, of the various disc-records produced, the three principal ones in use are identified by their spiral grooves as "lateral 30 cut", "sapphire-ball" and "diamond-point", also that different positions for the sound reproducer and diaphragms are required for disposing the styli in their playing positions; also that a greater pressure of the stylus is 35 required in a groove known as sapphire-ball than the other grooves mentioned, and that the stylus engaging in a diamond-point groove requires a lesser pressure than the others above named.

By use of the herein described invention, the sound reproducer may be rotated for moving it longitudinally of the sound conducting tube to dispose the stylus of any desired diaphragm in a playing position, 45 and simultaneously therewith supplying the required pressure for the stylus in the groove of the disc-record, no adjustments being required for operation after the sound reproducer has been disposed in its playing 50 position.

In the accompanying drawing which illustrates one embodiment of the invention, Fig. 1 is a plan view of the device. Fig. 2 is a view in side elevation of the sound

conducting tube, the sleeve for the three-part sound reproducer being in section. Fig. 3 is an end view showing the arrangement of the parts of the sound reproducer, parts being in section. Fig. 4 is a side view of the sound conducting tube showing 55 the sound reproducer mounted thereon. Fig. 5 is a side view of the sound conducting tube and sound reproducer. Fig. 6 is a plan view, partly in section, of the sound conducting tube. Fig. 7 is a side view of 60 the sound conducting tube. Fig. 8 is a sectional view on line 8—8 of Fig. 4. Fig. 9 is a sectional view on line 9—9 of Fig. 4. Fig. 10 is a sectional view on line 10—10 of Fig. 4. Fig. 11 is a detail relating to Figs. 70 6 and 7, being a transverse section through the sound conducting tube taken in the endless groove thereof.

Referring now to the drawing, numeral 1 indicates the conventional tone-arm of a 75 phonograph, the axis of its swinging movements being indicated at 2. At 3 is indicated a sound conducting tube provided at one of its ends with a weight 4, said tube having a pivotal mounting *a* between its ends upon the elbow *b* of the arm 1. The side wall of said tube is also provided with apertures 5 and 6, these being disposed at longitudinal intervals thereof and in non-aligning radial planes. The side wall of 85 the tube is also provided with an endless peripheral groove 7, having depressions *c*, *d* and *e* formed therein at intervals.

Numeral 8 indicates a sleeve provided with a three-part sound reproducer, said 90 parts being indicated at 9, 10 and 11, the stylus-bars for the diaphragms of these parts being respectively indicated at 9', 10' and 11', the styli for said bars being respectively indicated at 9'', 10'' and 11''. The 95 sleeve for the sound reproducer is also provided with a spring 12 and a partition 13, and in its side wall are formed apertures 14, 15 and 16.

Any suitable means may be provided for 100 rigidly mounting the three-part sound reproducer upon the sleeve 8, screws *f*, in the present instance, being shown for this purpose. However, it is obvious that the sleeve 8 may be cast integral with the sound reproducer, and for purposes of description, the sleeve may be considered as a part thereof.

Numerals 17 indicate the diaphragms,

and numerals 18 indicate the apertures for the sound reproducer, the apertures of parts 9, 10 and 11, respectively, of the sound reproducer being in constant communication 5 with apertures 14, 15 and 16 of the sleeve 8. Numeral 19 indicates a plunger which is mounted in an aperture 20 formed in the sleeve 8, said plunger normally being pressed inwardly by the spring 12 for engaging in 10 the groove 7.

It will be understood that the sleeve together with the parts 9, 10 and 11 of the sound reproducer, may be moved longitudinally of the sound conducting tube, the plunger 15 sliding in the groove 7, the sleeve also having a revoluble movement on said tube, simultaneously with its longitudinal movement, to dispose the styli of the three-part sound reproducer in playing positions; also 20 on account of the weight 4, when the sleeve is moved toward the pivot *a*, the pressure of a stylus upon the disc record 21 will be less than when moved in an opposite direction, the weight 4 upon the extension *g* of the 25 tube 3 being disposed at a fixed distance from said pivotal mounting *a*, these adjustments being desired since the pressure required for the stylus of the part 11 of the sound reproducer when it engages in a sapphire-ball groove is greater than the others mentioned, and the pressure required for the stylus 10" of the part 10 of the sound reproducer, when engaging in a diamond-cut groove is less than the others, and the 30 arrangement is such that when the sleeve is partly rotated for moving any one of the three parts of the sound reproducer longitudinally to its playing position, the stylus of said part will have the required 35 degree of pressure upon the disc record; also the construction is such that when the parts 9, 10 and 11 of the reproducer are in playing positions, their styli will be equi-distant from the pivotal mounting 2 of the tone- 40 arm 1.

In operation, the sleeve 8 may be rotated for disposing the part 9 of the sound reproducer in a vertical or playing position as shown in Figs. 1, 3 and 5, the resiliently 45 actuated plunger 19 then engaging in the depression *c* of the tube 3, which tends to prevent any movement of the sleeve or parts carried thereby, and this is the position of the sound reproducer when disc- 50 records are used which are provided with grooves known as lateral-cut, the apertures 5 and 14 being in register, the apertures 15 and 16 of the respective parts 10 and 11 of the sound reproducer being in non- 55 communication with the interior of the sound conducting tube, and as thus disposed a required degree of pressure is provided for the stylus 9" of the part 9 of the sound reproducer. 60

If an operator desires to use a disc record

having a groove known as sapphire-ball cut, the sleeve may have a revoluble movement to dispose the plunger in the depression *d* of the groove 7, the part 11 of the sound reproducer moving, as indicated by the arrow 70 in Fig. 3, in a circle's arc, to a horizontal position, the plunger operating to maintain the sleeve in stationary relation with the sound conducting tube 3, the apertures 6 and 16 being in register, the apertures 14 and 15 of the respective parts 9 and 10 of the sound reproducer being in non-communication with the interior of the sound conducting tube, and as thus disposed the pressure 75 for the stylus 11" of the part 11 of the sound reproducer upon the disc record will be of a required degree and greater than that of the other styli mentioned. Also the stylus of the part 11, when in its playing position, will be disposed at a distance from the pivotal mounting 2 of the sound-arm equal to that of the stylus 9" of the part 9 of the sound reproducer, when in its playing 80 position.

If it is desired to use a disc record having 85 a groove known as diamond-point, the sleeve 8 may be rotated to dispose the plunger in the depression *e* of said groove 7, the part 10 of the sound reproducer moving toward the pivotal mounting *a* and to a horizontal position, the apertures 6 and 15 being then in 90 register, the apertures 14 and 16 of the respective parts 9 and 11 being in non-communication with the interior of the tube 3, and since member 10 will be disposed nearer 95 to the pivotal mounting *a*, the pressure of its stylus upon the disc record will be less than the pressure of the other styli mentioned, and of a required degree. Also the stylus of the part 10 of the sound reproducer, when 100 in its playing position, will be disposed at a distance from the pivotal mounting 2 equal to that of the styli of the parts 9 and 11, when in their playing positions.

It will thus be seen that the sleeve 8 may 105 be moved longitudinally of the sound conducting tube for disposing any one of the three parts of the sound reproducer in playing position, the revoluble movement for this purpose being in either direction, the movements longitudinally of the tube for the parts 9, 10 and 11, respectively, being equal 110 to the distance between the depressions *e* to *c*, *c* to *d*, and *d* to *e* to dispose their respective styli equi-distant from the pivotal 115 mounting 2, when in their playing positions, and to provide the required pressure for each stylus upon its disc record.

While I have shown and described three 120 parts 9, 10 and 11 for the sound reproducer with their diaphragms disposed in non-parallelism, and prefer this construction, I 125 may employ a sound reproducer having a lesser or greater number of parts, and changes relating to minor details may be 130

made as found to be of advantage, all within the scope of the invention as claimed.

The sleeve 8 is provided with a rugose end portion $\frac{1}{2}$ for manual use when making adjustments of the sound reproducer longitudinally of the sound conducting tube.

I claim:

1. In an improvement in a phonograph having a pivotally mounted tone arm and having a sound-conducting tube provided with apertures in its side wall and pivotally mounted on the tone arm, an apertured sound reproducer rotatably mounted on said tube and provided with diaphragms and 15 stylus-bars, and means coactive with the rotation of the sound reproducer for moving it longitudinally of the tube to dispose one of its stylus-bars at a predetermined distance from the pivotal mounting of the tone 20 arm and to dispose one of its apertures in register with an aperture of said tube.

2. An improvement in a phonograph comprising a pivotally mounted tone arm, a sound-conducting tube pivotally mounted 25 upon said tone arm and having a counterbalance beyond its pivotal mounting, said tube having apertures in its side wall, an apertured sound reproducer rotatably mounted upon the sound-conducting tube 30 and provided with diaphragms and stylus-bars, and means for moving said sound reproducer longitudinally of the tube to modify its effective weight as compared with the weight of said counterbalance and to dispose 35 one of its apertures in register with an aperture of said tube and also to dispose one of the stylus-bars at a predetermined distance from the pivotal mounting of the tone arm, effective whenever said reproducer 40 is rotated.

3. An improvement in a phonograph, comprising in combination a tone arm, a sound-conducting tube mounted on the tone arm and having circumferentially spaced apertures 45 therein at longitudinal intervals, a sound reproducer provided with a plurality of diaphragms disposed in non-parallelism and having circumferentially spaced apertures therein at longitudinal intervals for registering with the apertures of the sound-conducting tube, said sound reproducer being movable longitudinally and rotatable for disposing one of its apertures in register with an aperture of the sound-conducting 50 tube, its remaining apertures being in non-register with the apertures of said tube.

4. In combination, a tone arm of a phonograph, a sound conducting tube pivotally mounted on the tone arm transversely of the 55 end thereof, said tube having an extension projecting beyond said pivotal mounting, a sound reproducer upon the other end of said tube away from said extension and movable longitudinally of the tube for counterbalancing the weight of the extension.

5. An improvement in a phonograph, comprising, in combination a tone arm, a sound conducting tube provided with circumferentially spaced apertures at longitudinal intervals, said tube being pivotally mounted on the tone arm and having a part extending beyond its pivotal mounting, a sound reproducer provided with a plurality of diaphragms disposed in non-parallelism and having circumferentially spaced apertures 70 formed therein at longitudinal intervals for registering with the apertures of the sound conducting tube, said sound reproducer being movable to counterbalance the weight of its extended part and to dispose one of its apertures in register with an aperture of the sound conducting tube with its remaining apertures in non-register with the apertures of said tube.

6. In a phonograph, a tone arm, a sound conducting tube having apertures in its side wall and pivotally mounted on the tone arm, and having an extension projecting beyond its pivotal mounting, a sound reproducer having a plurality of diaphragms disposed in non-parallelism and having apertures in its side wall communicating with said diaphragms, said sound reproducer being rotatably and longitudinally slidably mounted upon said tube to dispose one of its apertures 80 in register with an aperture of the tube and to counterbalance the weight of the extension of said tube.

7. In an improvement in a phonograph, a sound conducting tube provided with lateral apertures communicating with its interior and having an endless peripheral groove with depressions therein, a sound reproducer on the tube having a plurality of diaphragms with apertures to register with the lateral apertures of the sound conducting tube, a plunger mounted on the sound reproducer engaging in said groove and adapted to enter said depressions, said sound reproducer being adapted to have a revoluble movement for coactively causing a longitudinal movement thereof along the sound conducting tube to cause the aperture communicating with the unused diaphragm to be disposed in non-register with the apertures of said tube and cause the aperture communicating with the used diaphragm to register with one of the lateral apertures of the sound conducting tube.

8. In combination, a tone arm, a sound-conducting tube pivotally mounted thereon, said tube provided with lateral apertures and having an extension projecting to one side beyond its pivotal mounting, a sound reproducer provided with a plurality of diaphragms and having lateral apertures communicating with its interior and said diaphragms, said sound reproducer provided with manually operable means extending to one side of said pivotal mounting in a direc- 120

tion opposite to that of said first-mentioned extension for imparting a revoluble movement to the sound reproducer for moving it longitudinally of the tube to change its effective weight and to cause registration of an aperture of the sound reproducer with an aperture of the sound conducting tube.

In testimony whereof, I have affixed my signature in presence of two witnesses.

RALPH W. MORRISON.
